UNITED STATES PATENT OFFICE.

FRANK B. FELTON, OF BRIDGEPORT, CONNECTICUT.

GOLF-CLUB.

SPECIFICATION forming part of Letters Patent No. 723,258, dated March 24, 1903.

Application filed August 12, 1902, Serial No. 119,452. (No model.)

To all whom it may concern:

Be it known that I, FRANK B. FELTON, a citizen of the United States, and a resident of Bridgeport, in the county of Fairfield and State of Connecticut, have invented certain new and useful Improvements in Golf-Clubs, of which the following is a specification.

My invention relates to golf-clubs; and it consists in certain details of construction whereby the resiliency of the head of the club is improved.

To enable others to understand my invention, reference is had to the accompanying drawings, in which—

15 Figure 1 represents a view in perspective of a hollow metal club-head with a gutta-percha face and broken view of the wooden handle. Fig. 2 is a section of the head through $\alpha\alpha$ of Fig. 1. Fig. 3 is a detail perspective 20 view of the rubber shell adapted to be inserted within the cavity or recess of the head.

Its construction and operation are as follows:

25 1 represents the metal head, 2 the shank, and 3 the wooden handle.

4 is a rubber shell adapted to be inserted in the open mouth, recess, or cavity 1^a, Fig. 2, of the metal head.

30 5 is a gutta-percha core within said shell, and 6 is a gutta-percha face adapted to close the open mouth of the metal head.

It will be observed that the rubber shell 4 is shaped to conform to the interior walls of the cavity in the head, with its front vertical 35 face set back far enough so as to leave room for the gutta-percha face 6, which face is held in place by means of the lips 1^b in the front of the metal head 1.

After the rubber shell is inserted within 40 the cavity of the metal head 1 the said head is placed in a mold (not shown) and gutta-percha in a liquid state is forced through the hole 7 in the lower face of the head and rub-

ber shell into the interior of said shell to form the core 5. This liquid gutta-percha is 45 forced into the interior of the rubber shell 4 and through a suitable aperture in the mold (not shown) to form the striking-face 6, so that when cooled it will form a semisolid substance. This construction will impart to the 50 head the desired resiliency which the ordinary wooden head lacks and will result in causing a ball to be driven a greater distance, and it will also very materially reduce the shock felt when the ball is struck with the 55 solid head.

Having thus described my invention, what I claim as new, and desire to secure by Letters Patent, is—

1. The herein-described improvement in 60 golf-clubs, comprising, in combination, a metal head having a cavity in its front face, a rubber shell within said cavity, the interior of said shell filled with gutta-percha, under pressure, and a gutta-percha striking-face 65 overlying the front vertical face of the rubber shell, for the purpose set forth.

2. The herein-described improvement in 70 golf-clubs, comprising, in combination, a metal head having a cavity in its front face, a rubber shell inserted within said cavity so as to leave a space between the front face of 75 said shell and head, a gutta-percha striking-face inserted in the mouth of said cavity and means substantially as shown whereby said striking-face is held in place, the interior of said rubber shell filled with gutta-percha under pressure, for the purpose set forth.

Signed at Bridgeport, in the county of Fairfield and State of Connecticut, this 11th day of August, A. D. 1902.

FRANK B. FELTON.
